UNITED STATES PATENT OFFICE.

JAKE NIBLER, OF LA GRANDE, OREGON.

SIGNAL DEVICE.

Application filed October 29, 1924. Serial No. 746,594.

To all whom it may concern:

Be it known that I, JAKE NIBLER, a citizen of the United States, residing at La Grande, in the county of Union and State 5 of Oregon, have invented new and useful Improvements in Signal Devices, of which the following is a specification.

This invention relates to direction signals for motor operated vehicles, and more particularly to the manner in which the signal is mounted for operation, and the means utilized for throwing the signal to an active position and automatically returning it to its normal position.

More specifically stated, the invention contemplates the provision of an arm mounted for pivotal movement on the windshield standard, and normally arranged parallel therewith, together with means including a 10 foot actuated pedal for throwing the arm from a normal to a horizontal active position, the arm carrying a signal including a lamp casing which is automatically illuminated after it is moved from its normal to 15 its active position with said arm.

The nature and advantages of the invention will be better understood when the following detail description is read in connection with the accompanying drawing, the 20 invention residing in the construction, combination and arrangement of parts as claimed.

In the drawings forming part of this application, like numerals of reference indicate 25 similar parts in the several views, wherein:

Figure 1 is a perspective view of a portion of a motor operated vehicle showing how the signal is mounted thereon.

Figure 2 is a fragmentary view taken at 40 a right angle to Figure 1.

Figure 3 is a fragmentary view of a motor operated vehicle, showing in detail the means for operating the signal, and also 45 showing the normal and active positions of said signal by dotted lines.

Figure 4 is a sectional view taken on line 4-4 of Figure 2.

Figure 5 is a sectional view through the 50 signal.

Figure 6 is a similar view taken at a right angle to Figure 5.

The device forming the subject matter 55 of this invention includes an arm 10, the lower end of which is connected with a short lever 11 arranged at a right angle to said arm, and which lever is mounted for pivotal

movement in a manner to be presently described, and embracing one of the windshield standards at 12 is a two-part clamp, the respective parts of which are indicated 60 at 13 and 14, the latter being formed with an offset extension 15. Secured to this extension is a bracket 16, which parts are connected together by a fastening element 17. The extension 15 is of channel shape formation in cross section to slidably receive the bracket 16 as clearly shown in Figures 1 and 4. The bracket consists of a plate, and projecting from the opposite sides of this plate are lugs arranged in pairs, the lugs 70 of each pair being spaced apart as shown at Figure 4. Pivoted between the lugs 18 of one pair is the short lever 11 above referred to. This lever is provided with a segmental gear 19, which meshes with a similar gear 20 pivoted between the other pair of lugs 21 forming part of the bracket 16. Connected with the gear 20 is an operating rod 22, the gear 20 being formed with an extension 23 for this purpose. The rod 22 80 is arranged within the vehicle indicated at A, extending downwardly in the direction of the floor board, and pivotally connected with a lever 24 which is preferably arranged beneath the floor board B. The lever 24 is 85 pivoted on one end of a bracket 25, which bracket is secured to the underside of the floor board B by suitable fastening elements 26. This bracket is formed with a central opening which registers with an opening 27 90 in the floor board B, and operating through said openings is a foot actuated rod 28 surrounded by a coiled spring 28'. This spring normally holds the lever 24 in a true horizontal position, and returns the said lever 95 and its associated movable parts to their normal positions after each operation of the signal. Also secured to the underside of the floor board B is a contact 25' which is arranged in the path of movement of the roller 26' carried by the free end of the lever 24 so that when the roller engages the contact 25', the circuit will be closed to the bulb 20' arranged within the signal proper. It will be further noted upon inspection of 100 Figures 1 and 2 that the arm 10 can be swung from its normally vertical position outwardly to an active position by means of a handle 31' which projects rearwardly from the gear 20. This handle is arranged within 105 convenient reach of the operator of the vehicle, so that the single arm 10 can be 110

actuated either by hand through the instrumentality of the handle 31' or by depressing the foot operated rod 28.

As clearly illustrated in the drawings, the 5 arm 10 supports a signal in the nature of a lamp casing indicated at 29, and which casing is provided with front and rear lens of different colors indicated at 30. Arranged within the casing 29 is an electric light bulb 10 31 arranged in circuit with an electric switch, wherein the roller 26' constitutes the movable contact. When the lever 24 is depressed, the roller 26 is brought into engagement with the fixed contacts 25' secured 15 to the floor board of the car, so that in addition to moving the arm with its signal to an active position, the circuit to the bulb is caused to simultaneously illuminate the signal at night time. Arranged in this circuit 20 is a manually operable switch 33, which when opened allows the signal to be operated during the day time, without illuminating the signal as above described. As shown in Figure 2, the current passes from a suitable 25 source 34 to a fixed contact 31, a rod 35 leading from this contact through the arm 10 to the electric light bulb, the arm being hollow for this purpose. The current is then grounded through the frame of the vehicle. 30 In practice, the arm 10 together with the signal normally occupies the position shown in Figure 1, wherein the arm is received by a fork shaped bracket attached to the standard 12 of the wind shield. When it is desired to use the signal, the rod 28 is depressed more or less, to throw the signal from its 35 normal position to any one of the positions indicated at 36, 37, and 38 in Figure 3. If it is desired to turn to the right at the next 40 street intersection, the rod 24 is only lightly depressed to move the signal to the position indicated at 36 in Figure 3, whereas if it is desired to turn to the left, the rod 24 is depressed sufficiently to move the signal 45 to the position shown at 37 in Figure 2, while if it is intended to stop the vehicle, the rod

24 is fully depressed to move the signal arm 10 together with the signal to a position shown at 38 in Figure 3. It will be further noted that the plate 16 is provided with a 50 slot 39 to which the respective gears 19 and 20 mesh with each other. This can be accomplished by use of the handle 31'. The invention is not only simple in construction, and positive in operation, but it can be actuated and controlled without removing the hands from the steering wheel, thus allowing the operator to devote his undivided attention to the proper guidance of the vehicle. 55

While it is believed that from the foregoing description, the nature and advantages of the invention will be readily understood, I desire to have it known that I do not limit myself to what is herein shown and described, and that such changes may be 60 resorted to when desired as fall within the scope of what is claimed.

What is claimed is:

A vehicle signal operating means comprising an elongated bracket adapted to be secured to the underside of the floor board, and having a central opening therein, lugs depending from one end of said bracket, a lever pivoted at one end on said lugs and normally arranged parallel with said bracket projecting a slight distance beyond the forward end of said bracket, a vertically disposed operating rod connected at the forward end of said lever and operating through an opening in the floor board, a shank bifurcated at one end and straddling said lever to which it is secured, said shank sliding through the central opening of said bracket, a foot pedal carried by the upper end of said shank and utilized to operate said lever, and a coiled spring surrounding said shank and interposed between the bracket and said pedal for normally holding the lever parallel with the bracket and the signal inactive.

In testimony whereof I affix my signature.

JAKE NIBLER.
